TABLE LAMP

Harold Bloomfield and Daniel Bloomfield, both of Glen-coe, Ill., assignors to Bloomfield Industries, Inc., Chicago, Ill.

Filed Dec. 12, 1961, Ser. No. 67,895

Term of patent 14 years

(Cl. D48—20)

Fig. 1

Fig. 3

FIG. 1 is an elevational view of a table lamp showing our new design, the remaining three sides being the same; FIG. 2 shows a top plan view thereof; and

FIG. 3 is a cross section taken on the line 3—3 of FIG. 1.

We claim:

The ornamental design for a table lamp, substantially as shown and described.
